UNITED STATES PATENT OFFICE.

GEORGE F. READ, OF NEW YORK, N. Y., ASSIGNOR TO ROBERT HOE, OF NEW YORK, N. Y.

BED-MOVEMENT.

SPECIFICATION forming part of Letters Patent No. 746,741, dated December 15, 1903.

Application filed March 28, 1901. Serial No. 53,175. (No model.)

To all whom it may concern:

Be it known that I, GEORGE F. READ, a citizen of the United States, residing at New York, county of Kings, and State of New York, have invented certain new and useful Improvements in Bed-Movements, fully described and represented in the following specification and the accompanying drawings, forming a part of the same.

10 This invention relates to certain improvements in bed-movements.

In some types of bed-and-cylinder printing-machines the bed is reciprocated by means of a rotating gear, which engages alternately with upper and lower racks carried by the bed. The bed is provided with two pairs of abutments, one pair being located at each end of the bed, and the driving-gear carries a wrist-pin which, as the bed is finishing its 20 stroke in either direction and as the gear is running out of mesh with one rack preparatory to running into mesh with the other, engages between the abutments, brings the bed to a stop, and reverses its movement.

25 In machines such as have been referred to, the wrist-pin which is carried by the driving-gear is usually provided with a circular roll or bowl, the face of which does not correspond in shape with the face of the abutment. The 30 result of this construction is that the bowl has but a slight bearing-surface against the abutment, especially when the abutment is straight, and the excessive strain to which these parts are subjected in checking the 35 movement of the heavy bed causes them to wear, so that constant renewal is necessary.

It is one of the objects of this invention to produce a device for checking the movement of beds, such as have been referred to, in 40 which the engaging part shall be so constructed as to provide a large bearing-surface, thus reducing the excessive wear heretofore referred to.

A further object of the invention is to produce a mechanism for checking and reversing the movement of reciprocating beds in which abutments and engaging parts are employed, the said engaging part having a face or faces which correspond in outline with the 45 face or faces of the abutments, and being so

operated that its face or faces will be parallel with the face or faces of the abutments at the time when the two come into engagement.

With these and other objects in view the invention consists in certain constructions 55 and in certain parts, improvements, and combinations, as will be hereinafter described and then specifically pointed out in the claims hereunto appended.

In the accompanying drawings, which form 60 a part of this specification, and in which like characters of reference indicate the same parts, Figure 1 is a sectional side elevation of so much of a printing-machine as is necessary to an understanding of the invention. 65 Fig. 2 is a vertical cross-section of the machine shown in Fig. 1. Figs. 3 and 4 are plan views illustrating certain details of the construction. Figs. 5, 6, 7, 8, 9 are diagrammatic views illustrating the operation of the machine, and Fig. 10 is a detail sectional elevation illustrating the construction of the driving-gear and the parts immediately connected therewith.

Referring to the drawings, which illustrate 75 one embodiment of the invention, 1 indicates a frame of a printing-machine, which may be of any usual or desired construction. The frame is provided with ways 2, which operate to support a reciprocating bed of any 80 usual or desired construction. The means for reciprocating the bed may be varied within wide limits. In the preferred form of the construction, however, the bed is provided with a rack 4, which is secured to its under 85 side, and a rack 5, which is supported on or secured to a rack-frame 6, which is also secured to the under side of the bed. The rack 5 will preferably be integral with the frame, as shown, and the frame will be formed with 90 a way or groove on its under side which engages a guideway or runway 7, suitably supported in the frame. The purpose of this guide or run way is to assist in supporting the 95 rack and frame.

In the construction shown a rotating driver is employed for reciprocating the bed, said driver consisting of a gear 8, which is adapted to engage one of the racks to drive the bed in one direction and the other rack to 100

drive the bed in the opposite direction. In the preferred form of the construction the alternate engagement of the gear 8 with the racks will be effected by giving the gear a 5 rising-and-falling movement. To this end the gear is mounted on a stud 9, which is carried on a slide 10, said slide being guided in its vertical movement by ways 11, suitably mounted in the frame. The lower end of this 10 slide is provided with a bowl 12, which engages a suitably-formed groove in a cam 13, mounted on a shaft 14, supported in suitable bearings in the frame. While this construction for moving the gear is a preferred one, 15 other constructions may be substituted therefor.

The gear 8 may be driven in any suitable manner. In the construction shown it is driven by a pinion 15, mounted on a shaft 16, 20 which shaft may, if desired, be the power-shaft of the machine and be provided with a pulley 17, by which it is driven. In the construction shown the shaft 16 is further provided with a gear 18, which meshes with a 25 gear 19, mounted on a stud 20, suitably supported in the frame. Secured to the gear 19, so as to move therewith, is a pinion 21, which meshes with a gear 22, mounted on the shaft 14, before described as the shaft carrying the 30 slide-operating cam 13. It may be here remarked that the gearing just described is so proportioned that the shaft 14 makes one revolution for each complete reciprocation of the bed. The gear 18 also serves through an 35 intermediate 23 to drive a gear 24, which is secured to a shaft 25, which supports the cylinder 26, said shaft being mounted in bearings of any suitable description in the frame. In the construction described the gear 8 is 40 first caused to engage with one of the racks 45, thus causing the bed to move in one direction, these racks being of such a length as to cause the gear to drive the bed during the time in which it is to receive a uniform motion. At the time when the bed completes 45 its uniform motion, which is at about the time when the bed is finishing its stroke in either direction, the gear runs out of mesh with its co-operating rack, and the stopping 50 and reversing mechanism then assumes control of the bed and retains this control until the bed has completed its stroke, is reversed, and started in the opposite direction.

The details of the stopping and reversing 55 mechanism may be varied within wide limits. In the construction shown the bed is provided at each of its ends with a pair of abutments, the abutments at one end of the bed being marked 27 28 and the abutments at the other 60 end of the bed 29 30. These abutments will preferably be formed with straight or right line operating-faces, as shown, although the operating-faces of the abutments might be curved, if desired. Where, as in the preferred 65 construction, a pair of abutments at each end of the bed is employed, one of the

abutments of each pair will preferably be made movable, so as to permit the co-operating part of the stopping mechanism, to be hereinafter described, to come into engagement with the abutment, although constructions are possible and within the invention in which movable abutments are not used. 70

The means for moving the abutments when movable abutments are employed may be of 75 any suitable description. As shown, the abutment 28 is carried on arms 31, which are pivotally mounted in the frame, and said abutment has extending therefrom an arm 32, which preferably carries a bowl 33. Similarly, the abutment 30, which is also a movable abutment, is carried on arms 34, pivotally mounted in the frame, and has extending from it an arm 35, which is preferably provided with a bowl 36. Suitable cams are 80 provided with which the bowls engage to move the abutments at proper times. In the construction shown two such cams (see Fig. 2) 37 38 are employed, the cam 37 co-operating with the bowl 33 and the cam 38 with the 90 bowl 36. The cam 37 is located above the cam 38, and the bowl 36, which is carried by the arm 35, projects downward, while the bowl 33, which is carried by the arm 31, projects upward. 95

The means which co-operate with the abutments to check and bring the bed to a stop consists of an engaging part which moves in synchronism with the driving gear 8 and is preferably carried by said driving-gear. In 100 the preferred form of the construction this part will consist of a block 39, the faces of which correspond in shape to the operating-faces of the abutments. Inasmuch as in the present construction the operating-faces of 105 the abutments are straight the block is made rectangular in shape. As shown, the block is preferably square, in order to provide additional wearing-faces, which may be utilized by giving the block a quarter-turn. In the 110 construction shown this block is mounted on a stud 40, which is integral with a plate 41, secured to the gear 8 in any suitable manner, as by a screw 42. This plate is preferably provided with a perforation through which 115 the stud 9 passes. The block 39 is so mounted on the stud 40 as to be capacitated to have a movement independent of the rotating movement which it has in synchronism with the driver, and means is preferably provided 120 for controlling the movement of the block, so that at the time the block comes into engagement with the abutments its operating-faces will be parallel to the operating-faces of the abutments. 125

The means for controlling the movement of the block may be of any suitable description. In the construction shown, however, the block carries a pinion 44, which, as shown, is integral with the block. This pinion 44 is in mesh 130 with an intermediate 45, mounted on a bolt or stud 46, passing through the plate 41 and

the driving-gear 8, so as to assist in holding them together. This intermediate is in mesh with the stationary gear 47, which is mounted on or, as shown, formed on the stud 9, which supports the driving-gear 8. This stud 9, it may be remarked, is so mounted as to prevent any possibility of its turning. While this may be accomplished in any suitable manner, in the construction shown a pin 48 is provided which extends into the slide 10 and locks the stud in position with respect to this slide. As the driver rotates, therefore, it will be seen that the block will be given an independent movement, which is produced and controlled by the train of gears referred to, and these gears are so proportioned that at the time when the block comes into engagement with a pair of abutments its operating-faces will be parallel with the operating-faces 20 of the abutments, and this parallelism will continue during the time the parts are in engagement. This construction provides wide bearing-surfaces between the block and abutments, and thus greatly reduces the wear incident to the engagement of these parts.

The operation of the construction is as follows: The gear 8 is preferably so proportioned as to make three complete revolutions for each complete reciprocation of the bed. Referring to the diagram illustrated in Fig. 5, the gear 8 is shown in engagement with the lower rack 5 and the bed is finishing its stroke in the direction indicated by the arrow—that is, to the right of the observer as the construction is shown in Fig. 1. Inasmuch as the gear 8 has not passed out of mesh with the rack 5 the block 39 has not come into engagement with the operating-face of the abutment 29, but it will be seen that the operating-face of the block is parallel with the operating-face of the abutment. As the bed continues its movement the gear 8 passes out of engagement with the rack 5, and just as the gear 8 is about to pass out of engagement with the rack 5 the block 39 comes into engagement with the operating-face of the abutment 29, this position of the parts being shown in Fig. 6. At this time the movable abutment 30 has been operated by its cam 38, so as to pass in behind the block 39, the position of these parts being clearly shown in Fig. 3. As the gear 8 passes out of engagement with the rack 5 the block 39 assumes control of the bed. If the bed is running at a high speed, the abutment will by the momentum of the bed be forced up against the block 39 and the block will operate to check the movement of the bed. If, however, the bed is running at a low speed, the block operating against the movable abutment 30 will continue the movement of the bed.

Fig. 8 represents the position of the parts just at the instant when the bed is brought to a standstill and is about to reverse. In Fig. 9 the parts are represented at the time when the block and abutment have effected

the reversal of the bed and brought it up to the speed of the driving-gear 8, the said gear having in the meantime been moved up by its cam so as to run into engagement with the rack 4. As the bed begins to move ahead under the control of the gear and rack the cam 38 swings the movable abutment out of the plane of the block, so as to permit it to leave the abutment 29, this position of the parts being that shown in Fig. 4. The abutment will remain in its open position until the reciprocation of the bed is completed and the parts again reach the position shown in Figs. 3 and 6. When, however, the bed has reached that point in its movement in the direction indicated by the arrow in Fig. 4 at which the block 39 comes into engagement with the abutment 27, the roller 33 on the abutment 28 will have come into contact with its cam, and it will be swung in behind the block. At the time this happens the block and the abutment 27 assume control of the bed, the gear running out of mesh with the rack 4, and the reversal of the bed takes place, the operation being exactly the same as that before described.

The function of the movable abutments when the bed is running at the speed it ordinarily has when it is in operation is simply to hold the block and the stationary abutments in firm engagement and prevent any jumping. The momentum of the bed might under some circumstances be depended upon to effect the engagement referred to, and under such circumstances it is obvious that the movable abutments might be omitted.

While the construction which has just been described is a preferred embodiment of the invention, it is to be understood that it is not to be limited to such construction, but that many changes may be made therein without departing from the invention.

What is claimed is—

1. The combination with a reciprocating bed, of abutments carried by the bed, a rotating driver, a part carried by the driver but capacitated to have a movement independent of the rotating movement of the driver, said part having a face which corresponds in shape to the operating-faces of the abutments and being arranged to engage an abutment as the bed is finishing its stroke in each direction, and means for controlling the independent movement of said part so that its face will be parallel with the abutment at the time when the two come into engagement, substantially as described.

2. The combination with a reciprocating bed, of pairs of abutments carried by the bed and located at each end thereof, a rotating driver, a part carried by the driver but capacitated to have a movement independent of the rotating movement of the driver, said part having faces which correspond in shape to the operating-faces of the abutments and being arranged to engage a pair of abutments

as the bed is finishing its stroke in each direction, and means for controlling the independent movement of said part so that its faces will be parallel to the operating-faces of 5 the pair of abutments at the time when the part and abutments come into contact, substantially as described.

3. The combination with a reciprocating bed, of pairs of abutments carried by the bed, 10 an abutment of each pair being movable, a rotating driver, a part moving in synchronism with the driver and arranged to engage a pair of abutments as the bed is finishing its stroke in each direction, said part having faces which correspond in shape with the operating-faces of the abutments, and means 15 for moving said movable abutments out of and into the plane of movement of the part, substantially as described.

20 4. The combination with a reciprocating bed, of pairs of abutments carried by the bed, an abutment of each pair being movable, a rotating driver, a part carried by the driver and arranged to engage a pair of abutments 25 as the bed is finishing its stroke in each direction, said part having faces which correspond in shape with the operating-faces of the abutments, and means for moving said 30 movable abutments out of and into the plane of movement of the part, substantially as described.

35 5. The combination with a reciprocating bed, of pairs of abutments carried by the bed, an abutment of each pair being movable, a rotating driver, a part moving in synchronism with the driver but capacitated to have a movement independent of the rotating movement of the driver, said part having faces which correspond in shape to the operating-faces of the abutments and being arranged 40 to engage a pair of abutments as the bed is finishing its stroke in each direction, means for controlling the independent movement of said part, so that its said faces will 45 be parallel with the operating-faces of the abutments at the time when the part and the abutments come into contact and means for moving the movable abutments into and out of the plane of movement of the part, substantially as described.

50 6. The combination with a reciprocating bed, of pairs of abutments carried by the bed, an abutment of each pair being movable, a rotating driver, a part carried by the driver but capacitated to have a movement independent of the rotating movement of the driver, said part having faces which correspond in shape to the operating-faces of the abutments and being arranged 55 to engage a pair of abutments as the bed is finishing its stroke in each direction, means for controlling the independent movement of said part, so that its said faces will be parallel with the operating-faces of the pair of abutments at 60 the time when the part and said pair of abutments come into contact, and means for mov-

ing the movable abutments into and out of the plane of movement of the part, substantially as described.

7. The combination with a reciprocating bed, of abutments carried thereby, said abutments having right-line operating-faces, a rotating driver, and a block moving in synchronism with the driver and arranged to engage an abutment as the bed is finishing its stroke in each direction, said block having right-line faces, substantially as described.

8. The combination with a reciprocating bed, of abutments carried thereby, said abutments having right-line operating-faces, a rotating driver, and a block carried by the driver and arranged to engage an abutment as the bed is finishing its stroke in each direction, said block having right-line faces, substantially as described.

85 9. The combination with a reciprocating bed, of abutments carried thereby, said abutments having right-line operating-faces, a rotating driver, a block moving in synchronism with the driver but capacitated to have a movement independent of the rotating movement of the driver, said block having right-line faces and being arranged to engage an abutment as the bed is finishing its stroke in each direction, and means for controlling the independent movement of the block so that its face will be parallel with the face of the abutment at the time when the two come into engagement, substantially as described.

10. The combination with a reciprocating bed, of abutments carried thereby, said abutments having right-line operating-faces, a rotating driver, a block carried by the driver but capacitated to have a movement independent of the rotating movement of the driver, 105 said block having right-line faces and being arranged to engage an abutment as the bed is finishing its stroke in each direction, and means for controlling the independent movement of the block so that its face will be parallel with the face of the abutment at the 110 time when the two come into engagement, substantially as described.

11. The combination with a reciprocating bed, of pairs of abutments carried thereby, an 115 abutment of each pair being movable, a rotating driver, a block moving in synchronism with the driver and arranged to engage a pair of abutments as the bed is finishing its stroke in each direction, said block having right-line 120 faces, and means for moving the movable abutments into and out of the plane of movement of the block, substantially as described.

12. The combination with a reciprocating bed, of pairs of abutments carried thereby, 125 said abutments having right-line operating-faces, and an abutment of each pair being movable, a rotating driver, a block moving in synchronism therewith but capacitated to have a movement which is independent of its 130 rotating movement, said block being arranged to engage a pair of abutments as the bed is fin-

- ishing its stroke in each direction and having right-line faces means for controlling the independent movement of the block so that its faces will be parallel with the faces of the 5 pair of abutments at the time when the block and abutments come into engagement, and means for moving the movable abutments into and out of the plane of movement of the block, substantially as described.
- 10 13. The combination with a reciprocating bed, of abutments carried thereby and located at each end thereof, a rotating driver, a part rotating in synchronism with the driver but capacitated to have a movement independent 15 of its rotating movement, said part having a face which corresponds in shape to the operating-faces of the abutments and being arranged to engage an abutment as the bed is finishing its stroke in each direction, and 20 gears for controlling the independent movement of the part so that its face will be parallel with the face of the abutment at the time when the two come into engagement, substantially as described.
- 25 14. The combination with a reciprocating bed, of abutments carried thereby and located at each end thereof, a rotating driver, a block carried by the driver and having faces which correspond in shape to the operating-faces of 30 the abutments, said block being mounted to have a movement independent of its rotating movement, and gears for controlling the movement of the block, substantially as described.
- 35 15. The combination with a reciprocating bed, of abutments carried thereby and located at each end thereof, racks carried by the bed, a rotating driving-gear, means for causing the gear to alternately engage the racks, a 40 block carried by the gear, said block having faces which correspond to the operating-faces of the abutments and being arranged to engage an abutment as the bed is finishing its stroke in each direction, a gear on the block, a 45 stationary gear, the center of which substantially corresponds to the axis of the driving-gear, and an intermediate gear, whereby the block is held with its face parallel to the face of the abutment with which it engages, 50 substantially as described.
- 55 16. The combination with a reciprocating bed, of abutments carried thereby and located at each end thereof, said abutments having right-line operating-faces, racks carried by 60 the bed, a rotating driving-gear, means for causing the gear to alternately engage the racks, a block carried by the gear, said block having right-line faces which correspond to the operating-faces of the abutments and be- 65 ing arranged to engage an abutment as the bed is finishing its stroke in each direction, a gear on the block, a stationary gear, the center of which substantially corresponds to the axis of the driving-gear, and an intermediate gear, whereby the block is held with its operating-face parallel to the face of the abut-

ment with which it engages, substantially as described.

17. The combination with a reciprocating bed, of a pair of abutments carried thereby and located at each end thereof, said abutments having right-line operating-faces, racks carried by the bed, a rotating driving-gear, means for causing the gear to alternately engage the racks, a block carried by the gear, said block 75 having right-line faces which correspond to the operating-faces of the abutments and being arranged to engage a pair of abutments as the bed is finishing its stroke in each direction, a gear on the block, a stationary gear, the center of which substantially corresponds to the axis of the driving-gear, and an intermediate gear, whereby the block is held with its operating-faces parallel to the faces of the pair of abutments with which it engages, sub- 80 stantially as described.

18. The combination with a reciprocating bed, of abutments carried thereby and located at each end thereof, upper and lower racks carried by the bed, a rotating driving-gear, means 90 for moving the driving-gear in a straight line to cause it to engage first one of the racks and then the other, a block carried by the driving-gear and arranged to engage an abutment as the bed is finishing its stroke in each 95 direction, said block having faces which correspond in shape with the operating-faces of the abutments, a stationary gear, the center of which substantially corresponds to the axis of the driving-gear, and gearing driven by 100 said stationary gear for rotating the block so as to bring its operating-face into parallelism with the face of the abutment with which it engages, substantially as described.

19. The combination with a reciprocating bed, of abutments carried thereby and located at each end thereof, said abutments having right-line operating-faces, upper and lower racks carried by the bed, a rotating driving-gear, means for moving the driving-gear in a 110 straight line to cause it to engage first one rack and then the other, a block carried by the driving-gear, said block having right-line operating-faces which correspond to the operating-faces of the abutments and being arranged to engage an abutment as the bed is finishing its stroke in each direction, a stationary gear, the center of which substantially corresponds to the axis of the driving-gear, and gearing driven by 115 said stationary gear for rotating the block so as to bring its operating-face into parallelism with the face of the abutment with which it engages, sub- 120 stantially as described.

20. The combination with a reciprocating bed, of pairs of abutments carried by the bed and located at each end thereof, said abutments having right-line operating-faces, upper and lower racks carried by the bed, a slide, a rotating driving-gear mounted on the slide, 130 means for moving the slide to cause the driving-gear to engage with the upper and lower

racks, a block carried by the driving-gear and having right-line operating-faces, a stationary gear, the center of which substantially corresponds to the axis of the rotating driving-gear, and intermediate gearing between said stationary gear and the block, substantially as described.

In testimony whereof I have hereunto set my hand in the presence of two subscribing witnesses.
